UNITED STATES PATENT OFFICE.

EDWARD A. GEOGHEGAN, OF NEW YORK, N. Y., WILLIAM B. MAYO, OF HAMILTON, OHIO,
AND CHARLES S. TURNER, OF HIGHLAND PARK, MICHIGAN.

STEAM-SUPERHEATER.

1,216,253.

Specification of Letters Patent. Patented Feb. 13, 1917.

Application filed September 18, 1916. Serial No. 120,781.

To all whom it may concern:

Be it known that we, EDWARD A. GEOGHEGAN, WILLIAM B. MAYO, and CHARLES S. TURNER, citizens of the United States, residing, respectively, at the city of New York, in the State of New York, the city of Hamilton, county of Butler, in the State of Ohio, and the town of Highland Park, county of Wayne, in the State of Michigan, have 10 jointly invented certain new and useful Improvements in Steam-Superheaters; and we do hereby declare the following to be a full, clear, and exact description of the invention, such as will enable others skilled in the art 15 to which it appertains to make and use the same, reference being had to the accompanying drawings, and to the letters of reference marked thereon, forming a part of this specification.

20 This invention relates to steam superheaters, in which steam is received into and delivered from both ends thereof.

In large steam generating units the regulation of insurance underwriters requires 25 that there shall be two steam conductor mains leading from the generator, so that when a superheater is installed, there must be a steam connection between each conductor and the superheater, or a separate superheater for each conductor. To meet this 30 requirement of two steam conductors, we have devised a superheater having two headers, one of which is adapted to receive steam into both ends, and the other of which delivers superheated steam from both ends 35 thereof; also to provide means for draining the upper header. These and other features will appear hereinafter in the specification and claims, and are illustrated in the accompanying drawings, in which:—

40 Figure 1, is a side view partially in section, with the intermediate portion of the tubes broken away, of a superheater embodying our invention.

45 Fig. 2, is a diagrammatic view of a water-tube steam generator, with our improved superheater installed therein.

In these drawings A, indicates the upper or intake header; B, indicates the discharge header, and C, C', C', and C", C", groups of tubes connecting the headers A and B. In the ends of the intake header A, there are placed intake pipes which are sealed or welded 50 therein so as to form a steam tight joint 55 between the outer ends of the header A, and

said intake pipes A' A', the inner ends of said pipes A' A', being supported within the header A, by internal flanges a, which divide the interior of the header A, into three chambers a', a², a². The intake pipes A' A', 60 are not welded to the internal flanges a, but are free to move therethrough as the header A, and intake pipes A' A', are caused to expand or contract by variations in the temperature. The header B, has its interior divided by walls b b into chambers b', b², b², 65 the two chambers b² b², being in communication by means of a tube B', expanded into openings in the walls b b.

The group of tubes C, connect the chamber a', in the header A, and the chamber b', in the header B; and groups of tubes C' C', connect the chamber b', in the header B, and the chambers a² a², in the header A; and the groups of tubes C² C², connect the 70 chambers a² a² in the header A, and the chambers b² b², in the header B, so that steam enters the intermediate chamber a', 75 in the header A, and passes through the group of tubes C, into the chamber b', in the header B, and from the chamber b', through the two groups of pipes C' C', into the two chambers a² a², around the intake pipes A' A', in the header A, and from the chambers a² a² through the groups of tubes 80 C² C², into the chambers b² b², in the header B, from whence it is discharged into the steam main in the usual manner. It will therefore be observed, that by means of this 85 improved construction, the steam enters the header A, from opposite ends and travels through the intake pipes A', to the intermediate chamber a', and as the pipes A', are surrounded with partially superheated steam, the steam during its passage through 90 the pipes A' A', absorbs some heat therefrom, which assists in the superheating process. The tube B', connecting the chambers b² b², in the header B, equalizes the 95 pressure in said two chambers. It is obvious that the tubes C, C' and C², can be bent into any form desired, to adapt the superheater for installation in steam generators. In Fig. 2 is shown one form into 100 which said tubes can be bent so as to adapt the superheater to be used immediately behind the first bank of boiler tubes D, and under the second bank of tubes E. In this 105 form, one of the tubes of the groups C and C², is connected with the upper header A, 110

- at the under side thereof, as shown by the letter C³, in Fig. 2, so that any water which may accumulate in either of the chambers a', or a² a², in the upper header A, will pass 5 therefrom through said tubes C³, into the chambers b' and b² b², the water accumulating in the chambers b' passing therefrom through the small openings b³ b³, in the walls b b.
- 10 From the foregoing it will be obvious that while we have shown and described the headers A and B, as being divided into three chambers each, the same might be divided into five or more chambers, and the intake 15 pipes A' A', each pass through more than one division wall to the middle chamber; therefore it is not desired to be limited to the exact number of chambers and groups of connecting tubes shown and described.
- 20 Having thus fully shown and described this invention, so as to enable others to construct and utilize the same, what is claimed as new is:—
1. A superheater header comprising substantially a tubular member and adapted to have superheater tubes secured in the wall thereof, transverse walls within said header dividing the interior thereof into a plurality of chambers, and a steam intake pipe 25 longitudinally located within said header and communicating with the inner of said chambers, substantially as described.
  2. A superheater header comprising substantially a tubular member having closed 30 ends and adapted to have superheater tubes secured in the wall thereof, transverse walls
- within said tubular member dividing the interior thereof into a plurality of chambers, a steam intake pipe longitudinally located within said tubular member non- 40 slidably secured in one of the end walls of said header and slidably passing through the transverse walls between the inner and outer chambers, substantially as set forth.
3. In a superheater, a header, division 45 walls therein dividing the interior thereof into a plurality of chambers, intake pipes leading through said walls and outer chamber into each end of the middle chamber therein, another header, division walls 50 therein in staggered relation to the division walls in the first named header and forming a middle chamber therein, and a series of groups of tubes connecting the several chambers in one header with the chambers 55 in the other header, whereby steam introduced into the middle chamber in the first header will pass successively through all of the header chambers at each side of said middle chambers, substantially as set forth. 60
4. In a superheater, a header, division walls therein dividing the interior thereof into a plurality of chambers, and a tube therein connecting the outer chamber at one end of said header, with the outer chamber 65 at the opposite end thereof, substantially as set forth.

In testimony whereof we affix our signatures.

EDWARD A. GEOGHEGAN.
WILLIAM B. MAYO.
CHARLES S. TURNER.
